United States Patent Office.

CALVIN H. PAINE, OF PROVIDENCE, RHODE ISLAND, ASSIGNOR TO HIMSELF AND WILLIAM D. HILTON, OF THE SAME PLACE.

Letters Patent No. 65,592, dated June 11, 1867.

FENCE.

The Schedule referred to in these Letters Patent and making part of the same.

TO ALL PERSONS TO WHOM THESE PRESENTS SHALL COME:

Be it known that I, CALVIN H. PAINE, of the city and county of Providence, and State of Rhode Island, have invented a new and useful or improved Fence; and I do hereby declare the same to be fully described in the following specification, and represented in the accompanying drawings, of which—

Figure 1 is a side elevation.

Figure 2, a horizontal section; and

Figure 3, a transverse section of it.

The main body A of each section of this fence, or those portions of it enclosed between its horizontal rails and vertical posts, is made on the principle of the well-known "lazy-tongs," that is, of two series of bars jointed together at their crossings by a pin or bolt, c, going through the two bars at each crossing. The bars of one series are arranged parallel to each other, and so as to cross those of the other obliquely, they being also parallel, such being as represented, the whole being so that the connected series of bars may be contracted closely together or extended. The lazy-tongs body or section so made is to be placed or stretched between two vertical posts B B and into grooves d d made in their next adjacent sides, and it is also to rest in grooves e formed in a rail, C, and into grooves f f made in their next adjacent sides, and it is also to rest in grooves g formed in a rail, H, extending from one post to the other at or near their lower parts or the ground. A cap rail, D, fastened to the heads of the posts, is grooved along its under side, as shown at f, so as to receive the upper part of the lazy-tongs body. The frame, composed of the posts and rails, grooved as described, serves, while encompassing the lazy-tongs body, to prevent it from being either contracted or expanded. When taken out of the frame such body can readily be contracted lengthwise into less compass for being packed away or transported, as circumstances may require. The above makes an excellent fence for many purposes.

I am aware that it is not new to arrange two series of slats obliquely on one another, and fasten them together and firmly to posts and rails, in which case there is no jointing of the bars, so as to enable them to be worked or contracted and expanded on the principle of the lazy-tongs. I do not claim such a mode of making a fence, but—

I claim the fence as made with the "lazy-tongs," or folding section or body, arranged and combined either with grooved posts, or the same and rails, substantially as specified.

CALVIN H. PAINE.
